UNITED STATES PATENT OFFICE.

EDWARD J. GULICK, OF MISHAWAKA, INDIANA.

DESIGN FOR AN AUTOMOBILE-BODY.

40,639.

Specification for Design.

Patented Apr. 12, 1910.

Application filed September 14, 1909. Serial No. 517,729. Term of patent 14 years.

To all whom it may concern:

Be it known that I, EDWARD J. GULICK, a citizen of the United States, residing at Mishawaka, in the county of St. Joseph and State of Indiana, have invented a new, original, and ornamental Design for an Automobile-Body, of which the following is a specification, reference being had to the accompanying drawings, forming a part thereof.

The figure is a perspective view of an automobile body, showing my new design.

I claim—

The ornamental design for an automobile body, as shown.

EDWARD J. GULICK.
